UNITED STATES PATENT OFFICE.

ELMER LYMAN KOKANOUR, OF ROGERS, ARKANSAS.

MATRIX-CLEANER.

1,152,187.

Specification of Letters Patent. Patented Aug. 31, 1915.

Application filed May 6, 1915. Serial No. 26,272.

To all whom it may concern:

Be it known that I, ELMER L. KOKANOUR, a citizen of the United States, and a resident of Rogers, in the county of Benton and 5 State of Arkansas, have invented a new and useful Improvement in Matrix-Cleaners, of which the following is a specification.

My invention is an improvement in matrix cleaners, and the invention has for its 10 object to provide a machine of the character specified, especially adapted for cleaning and polishing the matrices used in linotype and intertype typesetting machines, wherein in a supporting table is provided having 15 rotating cleaning and polishing mechanisms over which the matrices are passed in succession until cleaned, and wherein stacking mechanism is provided for stacking the matrices after they are cleaned.

20 In the drawings: Figure 1 is a top plan view of the improved machine, Figs. 2, 4 and 5 are sections on the lines 2-2, 4-4 and 5-5 respectively, of Fig. 1, looking in the direction of the arrows adjacent to the line, Fig. 3 is a partial front view with parts in section, and Fig. 6 is an end view of the machine.

The present embodiment of the invention 30 comprises a supporting frame of approximately rectangular form and consisting of a rear longitudinal bar 1, a front longitudinally extending plate 2, and connecting end bars 3, for connecting the bar 1 and the plate 2. The bars 1, 2 and 3 are connected 35 to form a substantially rectangular frame, and the plate 2 is inclined as shown, inclining inwardly and upwardly toward the bar 1. The bar and the plate are connected intermediate their ends by a cross bar 4, and legs 5 are provided at the corners of the 40 supporting frame.

A shaft 6 is journaled longitudinally of the frame at approximately the center thereof in the cross bar 4 and one of the end bars 3, and the outer end of the shaft is provided 45 with a pulley 7 for engagement by a belt connecting the pulley with a suitable source of power, not shown. At its inner end the shaft 6 is provided with a bevel gear 8 and intermediate its ends with a similar gear 8^a, and the said gears mesh with bevel gears 9 and 9^a on the lower ends of vertical stub shafts 10 and 10^a journaled in a plate 11, 50 extending longitudinally of the support between the bar 1 and the plate 2. This plate

11 is arranged with its wide dimension perpendicular to the wide dimensions of the bars 1, 3 and the plate 2, and with its upper surface flush with the upper surfaces of the said bars 1 and 3, and disks 12 and 12^a are secured to the upper ends of the respective shafts 10 and 10^a. Each of the disks 12 and 12^a is provided with a hub 13, having one section 60 of a ball race on its lower end concentric with the shaft, and the other section 14 of the ball race encircles the shaft just above the plate 11. Series of balls 15 are arranged between the sections of the races, and each disk is thus supported by a ball bearing against downward thrust.

Sheets 16 and 16^a to be later described, 65 are secured to the upper faces of the disks 12 and 12^a, and the hubs of the disks are secured to the shafts so that when the shafts 10 and 10^a are rotated by means of the shaft 6 the disks will be rotated. A table 17 of sheet metal is arranged at that end of the table remote from the pulley 7, and the said table is connected at its outer end to a hinge block 18 secured on to the upper edge of the adjacent end bar 3, by means of hinges 19, the hinges being below the upper surface of the table 17. The inner edge of the table is recessed at its center as indicated at 20, and the said inner edge extends above the adjacent disk 12. The recess 20 is curved so that the edge of the table at the recess is 70 parallel with the periphery of the disk, and the table extends over the disk slightly, as shown more particularly in Figs. 1 and 2.

A bridge table 21 is arranged between the disks, and it will be seen that the upper surface of the bridge table is flush with the upper surface of the sheet 16 on the disk 12. The shafts 10 and 10^a are of unequal length, 75 the shaft 10^a being shorter than the shaft 10, so that the upper face of the sheet 16 of the disk 12^a is spaced slightly below the sheet 16 of the disk 12.

The difference in height between the disks 80 is equal to the thickness of the bridge table 21, and the said table is of sheet metal as shown. The opposite side edges of the bridge table are concave, each recess being shaped on an arc whose center is the adjacent stub shaft 10 or 10^a. The adjacent edge of the bridge table is spaced apart 85 from the adjacent edge of the disk 12, while the other edge of the bridge table extends above the disk 12^a as shown in Figs. 1 and 100 110

2, approximately the same distance as the inner edge of the feed table extends over the disk 12.

A third table 22 is arranged at the front 5 of the support adjacent to the plate 2, and the said table is hinged to the plate 2 as indicated at 23. The hinges 23 are near the ends of the plate or table and the said table is of sheet metal as is also the bridge table 10 21. The table 22 extends from the end of the support adjacent to the pulley 7 to and beyond the inner edge of the feed table 17, and the inner edge of the feed table 17 laps over the adjacent end of the table 22. The 15 inner end of the table 22 is recessed on arcs whose centers are the shafts 10 and 10^a, so that the inner edge of the said table will fit between and around the disks. The inner edge of the table is spaced apart from the 20 periphery of the disks as shown in Fig. 16, but between the disks the inner edge of the table 22 extends above the bridge table.

A shelf 24 extends forwardly from the lower edge of the plate 2, the said shelf being of angle material, consisting of two portions extending at an obtuse angle with respect to each other. One of the portions is secured to the under edge of the plate 2 by means of screws 25 or the like, and the other 30 portion extends outwardly from the outer face of the plate 2. At the end adjacent to the pulley 7, a species of casing is arranged on the shelf, the said casing consisting of a front plate 26 and an end plate 27, and a 35 portion of the material of the shelf is bent upwardly along the outer face of the end plate as indicated at 28.

A shaft 29 is journaled in the casing and perpendicular to the plate 2, and the plate 40 26, the said shaft extending through the casing and through the plate 2, and a pulley 30 is secured to the inner end of the shaft. A belt 31 connects the pulley 30 with a pulley 32 on the shaft 6, and at the corner of the 45 table direction elements 33 in the form of pulleys are arranged for supporting the belt, as it changes its direction. The pulleys 33 are journaled in U shaped brackets 34, and it will be evident that when the wheel 50 6 is rotated the shaft 29 will also be rotated.

A star wheel 35 is secured to the shaft 29 between the plate 26 and the plate 2, and an arc-shaped or curved chute 36 is arranged above the star wheel. The lower end of the 55 chute is just above the star wheel, and it will be noticed from an inspection of Fig. 3 that the sides of the chute are formed by the adjacent faces of the plates 2 and 26. The upper end of the chute is at the upper end 60 of the end plate 27 of the casing.

The bridge table 21 is supported by the body 37 of a bail, being held in bearing lugs 38 on the under surface of the table and at the ends thereof, and the arms 39 and 40 of 65 the bail are connected to the bar 1 and the

plate 2, as shown in Fig. 5. Each arm is provided with an eye, and these eyes fit against the inner surfaces of the bar 1 and the plate 2, and screws 41 are passed through the eyes to connect the arms to the bar and 70 the plate.

The operation of the device is as follows:—The shaft 6 is driven from any suitable source of power and this shaft is the driving shaft for the machine. The sheet 75 16 on the disk 12 is of cloth or felt, while the sheet 16 on the disk 12^a is of paper or like material. The disk 12 is the cleaning disk, while the disk 12^a is the polishing disk and both disks are rotated at a high speed 80 during the cleaning operation. The matrices to be cleaned are stacked in rows on the feed table from which they are drawn by the fingers of the operator on to the covering of the disk 12, and are held in contact 85 with the covering for a short time. They are then passed over the bridge table 21 on to the covering of the disk 12^a where they are again held for a considerable length of time. The matrices are then moved on to 90 the transfer table 22, and are turned over or reversed after which they are returned to the feed table 17. From the table 17 they are again fed in succession to the coverings of the disks 12 and 12^a, after which they 95 are drawn over the transfer table 22 to the stacking chute 36 and are permitted to slide down over the star wheel 35, which stacks them against a block not shown, mounted to slide on the shelf 24. This block is the 100 usual holding block, and merely moves over the shelf 24 to form a support for the ends of the row of matrices remote from the stacking sheet. All of the tables 17, 21 and 22 are hinged as described to permit them 105 to be swung upward and outward away from the cleaning disks, in order to permit cleaning or renewing of the disks. The coverings for the disks are held in place by any suitable means, as for instance, by rings 110 which engage the edges of the coverings.

I claim:—

1. A machine of the character specified, comprising a supporting table, a pair of stub shafts journaled vertically in the table and in spaced relation, a disk secured to the upper end of each stub shaft, a feed table hinged to the supporting table at one end thereof, and extending above the adjacent disk at its inner edge, a bridge table between the disks and detachably connected with the table, the disk adjacent to the feed table having a cleaning covering and being at a higher level than the other disk, the other disk having a polishing covering, and the bridge table having its upper surface flush with the covering of the disk adjacent to the feed table and extending over the covering of the other disk, a transfer table extending 120 from the inner edge of the feed table along 125 130

- side the disks to the opposite end of the table and hinged to the front of the table to swing outwardly away from the disks, said table having at the front thereof a plate 5 inclining downwardly and outwardly and provided at its lower edge with a ledge or shelf for receiving the cleaned matrices, a star wheel journaled on an axis perpendicular to the plate above the shelf and at the 10 end remote from the feed table, a stacking chute delivering above the star wheel, means for simultaneously rotating the disks, and a driving connection between the said means and the star wheel.
- 15 2. A machine of the character specified, comprising a supporting table, a pair of stub shafts journaled vertically in the table and in spaced relation, a disk secured to the upper end of each stub shaft, a feed table 20 hinged to the supporting table at one end thereof, and extending above the adjacent disk at its inner edge, a bridge table between the disks and detachably connected with the table, the disk adjacent to the feed table 25 having a cleaning cover and being at higher level than the other disk, the other disk having a polishing cover, and the bridge table having its upper surface flush with the cover of the disk adjacent to the feed table, 30 and extending over the covering of the other disk, a transfer table extending from the inner edge of the feed table alongside the disks to the opposite end of the table and hinged to the front of the table to swing outwardly away from the disks, said table having at the front thereof a plate inclining 35 downwardly and outwardly and provided at its lower edge with a ledge or shelf for receiving the cleaned matrices, and means 40 for driving the disks.
3. A machine of the character specified, comprising a supporting table, a pair of stub shafts journaled vertically in the table and in spaced relation, a disk secured to the 45 upper end of each stub shaft, a feed table hinged to the supporting table at one end thereof, and extending above the adjacent disk at its inner edge, a bridge table between the disks and detachably connected with the 50 table, the disk adjacent to the feed table having a cleaning covering and being at a higher level than the other disk, the other disk having a polishing covering and the bridge table having its upper surface flush 55 with the covering of the disk adjacent to the feed table, and extending over the covering of the other disk, a transfer table extending from the inner edge of the feed table alongside the disks to the opposite end of the 60 table and hinged to the front of the table to swing outwardly away from the disks, and means for driving the disks.
4. A machine of the character specified,
- comprising a supporting table, a feed plate hinged to the table at one end and extending inwardly above the table, a pair of horizontal disks journaled on the table on vertical axes and spaced apart longitudinally of the table, one of the disks extending beneath the inner edge of the feed table and 65 being at a higher level than the other disk, a bridge table between the disks and detachably connected with the table for transferring the matrices from the first-named to the last-named disks, a transfer table hinged 70 to the front of the supporting table extending upwardly and outwardly, and extending above the transfer table, said disks having coverings of cleaning and polishing material, and a common means for driving 75 the disks.
5. A machine of the character specified, comprising a supporting table, a polishing disk journaled near one end of the table on a vertical axis, a cleaning disk journaled intermediate the ends of the table on a vertical axis, a feed table extending from the adjacent end of the table over the cleaning disk, a bridge table between the disks, and a transfer table in front of the disks, said 80 table having a receiving shelf or ledge below the transfer table and in front thereof and having an inclined plate leading downwardly to the said ledge, and means for simultaneously rotating the disks, said feed 85 and transfer tables being hinged to the supporting table to swing upwardly and outwardly away therefrom, and the bridge table being detachably connected with the supporting table.
6. A machine of the character specified, comprising a supporting table, a polishing disk journaled near one end of the table on a vertical axis, a cleaning disk journaled intermediate the ends of the table on a vertical axis, a feed table extending from the adjacent end of the table over the cleaning disk, a bridge table between the disks, and a transfer table in front of the disks, said 90 table having a receiving shelf or ledge below the transfer table and in front thereof and having an inclined plate leading downwardly to the said ledge, and means for simultaneously rotating the disks.
7. A machine of the character specified, comprising a supporting table, cleaning and polishing disks journaled on the table on vertical axes, means for driving the disks, said table having a receiving shelf below the level of the table and at the front thereof and having an inclined plate leading to the said shelf, a star wheel journaled between the incline and the shelf for engaging 105 and stacking the matrices as they are cleaned.

ELMER LYMAN KOKANOUR.
